WAXING ATTACHMENT

Thomas S. Lytton, Gastonia, N. C., assignor of
one-half to Benjamin F. Austin, Gastonia,
N. C.

Application July 20, 1939, Serial No. 285,579

3 Claims. (Cl. 91—36)

This invention relates to a waxing attachment for spoolers, spinning frames, winders and the like and more especially to what is termed as "cake waxing."

It is common practice in mills to pass a strand of yarn in contact with a cake of solidified wax in order that wax might be applied to the periphery of the strand. In many instances the cake of wax is rotatably mounted around a pin which extends upwardly from a base member. The strand is drawn between the lower surface of the cake and the upper surface of the base member, and while passing therebetween, a coating of wax is applied to the strand. Due to the fact that the temperature runs rather high in mills, there is a tendency for the cake of wax to partially melt and become distorted so that it will not rotate around the pin as the strand is drawn past the lower surface of the cake. This failure of the cake of wax to rotate allows the strand to cut a groove in the lower portion thereof, after which the yarn will collect very little wax.

It is, therefore, an object of this invention to provide a waxing attachment comprising a base member with a flat upper surface over which the strand is adapted to be drawn and a pin rising from the central portion thereof with an inverted cup member rotatably mounted around said pin. The cup member has a cake of waxing material loosely mounted therein which rests upon the strand and upon the upper side of the base member. This cup member prevents lateral distortion of the cake due to excess heat thereby keeping the bearing area on the lower face of the cake substantially the same at all times. As the strand is drawn beneath the cake member the cake will rotate to deposit wax on all portions of the yarn.

It is a further object of this invention to provide an apparatus of the class described having means disposed in the cup for weighting the top of the cake so that the necessary pressure will be applied by the lower portion of the cake upon the strand. This weighting member also keeps the top surface substantially level, thereby preventing distortion and causes the cake to feed downwardly as the lower bearing surface is worn off.

It is a further object of this invention to provide a waxing attachment of the class described having means for indicating the thickness of the cake of wax remaining in the cup at all times.

Some of the objects of the invention having been stated, other objects will appear as the description proceeds when taken in connection with the accompanying drawing, in which—

Figure 1 is a plan view of an improved waxing

attachment shown in conjunction with a tension device and a slab catching device;

Figure 2 is a vertical sectional view taken along the line 2—2 in Figure 1;

Figure 3 is an exploded isometric view of the invention.

Referring more specifically to the drawing, the numeral 10 denotes a suitable transverse rod of a spooler, winder, spinning frame or the like, upon which is secured a bracket 11. This bracket has 10 an eyelet 12 therein through which a strand of yarn 14 is adapted to pass. From this eyelet the yarn passes between disks 15, and 16, which act as a tension device. The upper disk 16 is weighted by a suitable washer 17, the number of which may be varied depending upon the amount of tension desired to be exerted upon the yarn. All of the members 15, 16, and 17 are rotatably mounted around a pin 18, which is anchored in bracket 11.

The central portion of the bracket 11 has a pin 20 19, extending upwardly therefrom around which is rotatably mounted a member 20. This member 20 has a base portion 21 and an upwardly extending cylindrical projection 22, said projection having a hole 23 in the central portion thereof which 25 is adapted to rotatably fit over the pin 19. The projection 22 of the member 20 is adapted to fit in a cylindrical hole 24 in sleeve 25. The sleeve 25 forms an integral part of a cup member 26. By referring to Figure 2, it will be seen that the lower 30 rim of sleeve 25 normally rests upon base portion 21 and is slightly lower than the rim of the cup 26. This allows the rim of the sleeve 25 to support the cup when it is in an inverted position and also allows the strand of yarn 14 to pass beneath the rim of the cup member 26 without contacting the same. Disposed within the cup member 26 and around the sleeve 25 is a cake of waxing material 27, such as paraffine and the like. This cake is cylindrical in shape and has a hole 40 28 in the central portion thereof for fitting around the sleeve 25.

When the cake 27 is disposed in the cup 26 in the manner shown in Figure 2, the lower surface thereof normally rests on the top of the base 45 portion 21 of member 20 thereby binding the strand 14 therebetween. Due to the fact that the cup member 26 is rotatably mounted around the upstanding projection 22 and since the member 20 is also rotatably mounted around its associated pin 19, it is seen that upon drawing the strand of yarn 14 beneath the wax that a rotary motion will be imparted to the wax cake, thereby causing the lower portion of the wax to be evenly worn by the passing strand. Since the 50 55

periphery of the cake 27 is held by the sidewalls of the cup member 26, it is impossible for this cake to become laterally distorted any appreciable amount even though it is subjected to relatively high mill temperature.

It has been found necessary in some instances to provide a suitable weighting means on top of the cake of wax 27 and within the cup 26, so that the necessary downward pressure will be exerted upon the cake of wax. Therefore a washer 35 has been provided with a hole 35a therein, said washer being mounted around sleeve 25 and on the top of cake 27. This washer may be of any desired thickness, depending upon the amount of weight desired to be exerted upon the wax. Studs 36 and 37 are secured in opposed sides of the washer, said studs being adapted to penetrate the slots 38 and 39 respectively in the cup 26. The pins 36 and 37 are visible from the exterior of the cup and thereby furnish means for indicating the amount of wax within the cup. The slots 38 and 39 also serve as a guide for the washer as it moves downwardly. This washer, in addition to furnishing weight to the cake of wax 27, also serves to maintain the top side of the cake substantially level and prevents distortion.

After the strand 14 leaves the waxing attachment, it is adapted to pass beneath a bar 40 and over a plate 41. Disposed above the plate 41 at a slight distance from the top of the strand 14 is a comb 42, which serves to receive slubs from the strand.

In the drawing and specification there has been set forth a preferred embodiment of the invention and although specific terms are employed, they are used in a generic and descriptive sense only and not for purposes of limitation, the scope of the invention being set forth in the appended claims.

40 I claim:

1. Apparatus for applying wax to a strand, comprising a rotatable disk, means for passing a strand over the upper surface of the disk, an upstanding portion integral with the center of said disk, an annular cake of wax disposed around said upstanding portion and having a substantial clearance between the inner surface of the wax and the upstanding portion, means for passing a strand between the lower surface of the

wax cake and the disk member, an inverted cup-shaped member disposed over and around the wax for confining the wax and retaining the wax in its annular condition, and an annular member disposed within the cup and resting on the upper surface of the cake of wax for pressing the wax into contact with the strand. 5

2. In a winding machine, spooler and the like, means for applying wax to a strand comprising a rotatable disk member, means for passing a strand over the upper surface of the disk member, an upstanding portion disposed centrally of the disk member, an annular cake of wax disposed around said upstanding portion and having a substantial clearance between the inner periphery of the annular cake of wax and the upstanding portion, a cup-shaped member adapted to fit over the cake of wax and having a central tubular portion adapted to fit between the inside periphery of the cake of wax and the upstanding portion, a washer member disposed within the cup shaped member, the walls of the cup shaped member having a pair of opposed slots therein, and projections on said washer disposed in said slots for guiding the washer and at the same time indicating the thickness of wax cake remaining within the cup-shaped member at all times. 15 20 25

3. A waxing attachment for winders, spoolers and the like for applying wax to a strand being wound, a rotatably mounted disk member, means for guiding a strand along the upper surface of the disk member, an upstanding centrally located portion integral with the disk member, an inverted cup shaped member having a pair of concentrically disposed tubular portions defining an annulus, an annular cake of wax disposed in said annulus and having its lower surface adapted to rest against a strand passing along the upper surface of the disk member, an annular washer disposed within said annulus, to press the cake 40 of wax downwardly in said annulus to hold it in contact with the strand, the outermost tubular portion having a pair of opposed slots therein, said washer having a pair of opposed pins in its periphery adapted to loosely project into said 45 slots to guide said washer and also serving as an indicator to indicate the thickness of the cake of wax at all times. 30 35 45
